UNITED STATES PATENT OFFICE.

REUBEN L. FERGUSON, OF HONDALE, NEW MEXICO.

LIQUID SEAL FOR PUMPS.

1,401,060.

Specification of Letters Patent. Patented Dec. 20, 1921.

Application filed October 13, 1916. Serial No. 125,395.

To all whom it may concern:

Be it known that I, REUBEN L. FERGUSON, a citizen of the United States, residing at Hondale, in the county of Luna and State 5 of New Mexico, have invented certain new and useful Improvements in Liquid Seals for Pumps; and I do hereby declare the following to be a full, clear, and exact description of the invention, such as will enable 10 others skilled in the art to which it appertains to make and use the same.

The invention relates to a liquid seal for pumps.

The object of the present invention is to 15 improve the construction for pumps and to provide a liquid seal of simple and comparatively inexpensive construction adapted to reduce to a minimum friction of the moving parts of a pump and capable of eliminating 20 costly and inefficient sucker rods and similar suction devices and of providing a construction adapted to be operated by a cable drive.

A further object of the invention is to 25 provide a pump of this character which when operated by a cable drive will respond quickly on the downward or gravity stroke so that a rapid operation of the pump will be effected.

30 With these and other objects in view the invention consists in the construction and novel combination and arrangement of parts hereinafter fully described, illustrated in the accompanying drawings and pointed out in 35 the claims hereto appended, it being understood that various changes in the form, proportion and minor details of construction may be resorted to without departing from the spirit or sacrificing any of the advantages of the invention.

In the drawing—

Figure 1 is a vertical sectional view of a pump provided with a liquid seal constructed in accordance with this invention.

45 Fig. 2 is a horizontal sectional view on the line 2—2 of Fig. 1.

Like numerals of reference designate corresponding parts in the several figures of the drawing.

50 In the accompanying drawing in which is illustrated the preferred embodiment of the invention, the pump comprises in its construction a lower sealing member 1 and an upper member 2, the upper and lower members having relative movement for forcing water or other liquid through the pump into

a discharge pipe 3. The lower sealing member consists of inner and outer walls or cylinders arranged concentric with each other and spaced apart to provide an intervening seal receiving space 6 and connected at their lower ends at 7 for closing the seal receiving space. The upper cylinder extends into the seal receiving space 6 and while in the accompanying drawing the 60 upper and lower members are shown in cylindrical form they may of course be of any other configuration. The lower terminal portion 8 of the lower seal receiving or sealing member is enlarged and provided 70 with a seat 9 for a check valve 10 adapted to operate in the usual manner to permit a liquid to enter the pump on one stroke and to close and prevent the escape of liquid from the pump on the other stroke. In the 75 pump shown in the accompanying drawing the lower sealing member is vertically movable and the valve opens on the downward stroke and closes on the up stroke but with some pumps it may be desired to reverse the 80 movement of the parts and the lower sealing member may be stationary and the upper member movable as will be readily understood.

Within the space 6 of the lower sealing member is arranged a liquid 11 of a greater specific gravity than the liquid to be pumped, say for instance, mercury, when water is pumped. The height of the column of liquid in the sealing space or chamber 6 is proportional to the pressure of the column of water lifted by the pump as it is necessary for the sealing liquid to exert sufficient pressure to sustain the weight of such column of water and prevent leakage of the water or other liquid operated on by the pump. When mercury is employed in a water pump the column of mercury will be at least thirty inches in height for each thirty-two feet of pumping head as will be readily understood. 100 When there is relative movement of the upper and lower members of the pump the sealing liquid at the inner side or face of the upper member is compressed until the pressure equals the pressure of the column 105 of liquid lifted by the pump and the outer wall or cylinder of the lower member is preferably provided at its upper portion with a horizontal annular enlargement 12 which forms a receptacle for preventing any overflow of the liquid of the sealing chamber or space 6. As it is unnecessary to provide

a tight fit between the upper and lower relatively movable members of the pump, the said members will not be worn and rendered inoperative by sand and other solid particles and the pump is also adapted to obviate the necessity of employing sucker rods and similar construction which are not only costly but are rapidly worn out by the cutting of leather by sand and the like and 10 which become worthless when the piston fails to make a water tight fit in the cylinder.

In the pump illustrated in the accompanying drawing the lower sealing member is provided with a shank or rod 13 extending 15 through a stuffing box 14 of the upper member and secured at its lower end to a spider or frame 15 of the inner cylinder of the lower member by nuts 16 or other suitable fastening means. The shank or rod 13 is 20 provided at the outer end with suitable means for connecting it to an operating rod or a cable drive and a coiled spring 17 is mounted within the upper portion of the upper member and is adapted to be compressed 25 on the upward stroke or movement of the lower member whereby it will operate to cause a quick or sudden movement of the lower member in the downward action of the pump. This is important when a cable 30 drive is employed as the downward or gravity stroke will be rapid and will not depend entirely on gravity. The discharge pipe 3 is provided with suitable check valves 18 arranged in a horizontal portion 19 and 35 adapted for use in a double acting pump, the horizontal portion of the discharge pipe being designed to be connected at each end with an upper member 2. While the lower movable member is shown connected with 40 the operating means by the interior rod 13 the construction may be simplified by providing an exterior connection between the movable member and the operating means.

The inner wall or cylinder of the lower 45 member of the pump is provided at its upper portion with an annular flange 19^a ex-

tending from the inner face of the said wall or cylinder and forming a seat for the lower end of the coiled spring.

What is claimed is:—

1. A pump comprising a vertical pipe open at its lower end, a cylinder having a head at its lower end provided with an internal chamber having a restricted inlet, a loosely mounted valve disk within the chamber normally closing the inlet, an outer tubular sleeve extending from the head in spaced relation to the cylinder with the pipe loosely fitting between the sleeve and cylinder, the space between the sleeve and cylinder being closed at the lower ends thereof to provide a fluid pocket forming a fluid seal for the lower end portion of the pipe, an actuating rod secured within the inner sleeve and extending upwardly through the pipe, and a spring engaging the cylinder to yieldably hold the cylinder against vertical movement. 55

2. A pump including an upper cylinder, a lower cylinder having a bore of uniform 70 diameter throughout its entire length and having an outer concentric mercury containing chamber receiving the lower end of the upper cylinder, the outer wall of said chamber being enlarged laterally at a point below its upper end and contracted above this point to provide a spill or overflow chamber 75 opening into the mercury chamber only.

3. A pump including an upper stationary cylinder, a lower working cylinder, an intake valve in the lower end of said working cylinder, a mercury chamber concentric with and surrounding said working cylinder and receiving the lower end of the upper stationary cylinder, and actuating means for 80 85 said working cylinder.

In testimony whereof I affix my signature in presence of two witnesses.

REUBEN L. FERGUSON.
